J. PILNY ET AL.

OPERATING MEANS FOR CURTAINS

Filed April 7, 1923

UNITED STATES PATENT OFFICE.

JOHN PILNY, OF NEW BRIGHTON, AND WILLIAM KUEHN, OF ELMHURST, NEW YORK.

OPERATING MEANS FOR CURTAINS.

Application filed April 7, 1923. Serial No. 630,555.

To all whom it may concern:

Be it known that we, JOHN PILNY and WILLIAM KUEHN, citizens of the United States, and residents, respectively, of the 5 city of New York, New Brighton, Staten Island, borough of Richmond, in the county of Richmond and State of New York, and of the city of New York, Elmhurst, Long Island, borough of Queens, in the county of 10 Queens and State of New York, have invented a new and Improved Operating Means for Curtains, of which the following is a full, clear, and exact description.

This invention relates to curtains, portières 15 and other hangings and has particular reference to means for operating the same.

An object of the invention is to provide an operating means for curtains and the like which will facilitate the adjustment of a 20 curtain to its opened or closed position.

Another object is the provision of an operating means of simple and inexpensive construction which, in position in association with a curtain, will be practically invisible 25 so as not to detract from the neat and attractive appearance of the curtain.

The above and other objects will appear more clearly from the following detail description, when taken in connection with the 30 accompanying drawing, which illustrates a preferred embodiment of the inventive idea.

In the drawing—

Figure 1 is a front elevation of the invention, partly broken away and shown in 35 section, and illustrating the parts in the position they assume at the beginning of the movement of the curtain toward its opened position;

Figure 2 is a section substantially on the 40 line 2—2 of Figure 1;

Figure 3 is a section on the line 3—3 of Figure 1; and

Figures 4 and 5 are detail perspective 45 views of the brackets utilized for supporting the trackway.

Referring more particularly to the accompanying drawing, the numeral 6 indicates generally the frame of a doorway or other opening which is designed to be closed by 50 the curtain 7 made of any desirable material.

The invention is shown as comprising a pair of brackets, generally indicated by the numerals 8 and 9, made of any suitable material, such as sheet metal. The bracket 8, 55 which is in the form of an open ended cas-

ing, is secured to one side of the frame 6 adjacent the upper end thereof and is provided in the bottom 10 thereof with a slot 11 for a purpose which will presently appear. Extending across the bottom 10 transversely to the slot 11 is a strip 12 which limits the inward movement of the end of a trackway 13, which is first inserted into the open end of the bracket 8 when the trackway is being mounted in position. By thus limiting the inward movement of the end of the trackway the same is prevented from coming in contact with the pulleys 14 which are suspended from the top 15 of the bracket. The bottom 10 is further provided with a cut-out portion 16 directly below the pulleys 14 to provide an opening through which the ends of the operating cords 17 for the curtain 7 extend. After one end of the trackway 13 has been inserted into the bracket 8 the opposite end thereof is lowered into engagement with the bracket 9 secured to the opposite side of the doorway, the bottom 18 of said bracket being also provided with a slot 19 which is in alignment with the slot 11 of the bracket 8. The end of the trackway 13 which is inserted into the bracket 9 is provided with a cross piece 20 to which is secured the pulley 21, the axis of rotation of which is transverse to that of the pulleys 14.

The trackway 13 is channel shaped in formation, as best shown in Figure 3, and is provided with an open top and in the bottom thereof with a longitudinally extending slot 22 extending the entire length of the trackway and registering with the slots 14 and 19 in the brackets 8 and 9 when the trackway is in position. The sides of the trackway are braced by means of a plurality of cross bars 23 secured to the upper edges of said sides.

Mounted for longitudinal movement with respect to the trackway 13 are a plurality of carriers each of which includes a shaft 24 which is disposed transversely of the trackway and which carries the rollers 25 at each end thereof arranged on opposite sides of the slot 22. Certain of the carriers each supports a hanger 26 having its upper end pivotally mounted on the shaft 24 of the associated carrier between the rollers 25 thereon and its lower end provided with an opening 27 for receiving a hook 28 secured to the upper portion of the curtain 7 between the folds 29 thereof so that the hook

will be invisible from either side of the curtain. The carrier disposed on the trackway 13 nearest to the free end of the curtain 7 and to which an intermediate portion of the 5 operating cord 17 is attached, as best shown in Figure 2, supports a hanger consisting of the upper and lower sections 30 and 31, the latter of which is pivotally connected to the former by a link 32 which permits of 10 a swinging movement of the section 31, as indicated in Figure 1, when the curtain is being moved to open or closed positions. The lower end of the section 31 is of the 15 same construction as the other hangers 26 and is also attached to the curtain by means of a hook similar to the hooks 28.

As seen in Figures 1 and 2, the operating cord 17 is passed around the pulleys 14 and 21 and joined to the carrier at the 20 extreme left, the ends of the operating cord depending from the pulleys 14 and through the opening 16 in the bracket 8 so that said ends may be readily grasped to move the curtain to open or closed position. In 25 Figure 1, the curtain is shown at the beginning of its movement toward the open position during which movement a pull is exerted upon the carrier shown at the extreme left in a direction toward the fixed end of 30 the curtain which is attached to the frame 6 by a suitable fastener 33. By reason of this pull the lower section 31 of the left-hand hanger will be caused to assume an 35 angular position with respect to the vertical, as shown in Figure 1, and as the curtain is moved to the right the same will fold, as indicated in said figure. The relative movement between the sections 30 and 31 permits the carrier supporting the same 40 to move freely along the trackway with the upper section 30 in its normal vertical position. As the movement of the curtain progresses toward its open position, each carrier is engaged by the preceding carrier 45 at the left and caused to move along the trackway toward the fixed end of the curtain. When the opposite end of the cord 17 is pulled the carriers are moved to the left in the trackway until the carrier supporting 50 the hanger including the sections 30 and 31 reaches the left-hand end of the trackway. In this movement the section 31 will assume the position opposite to that shown in Figure 1 and upon the carriers supporting 55 said section reaching the end of the trackway the section 31 will be moved to a vertical position by the weight of the curtain and in so doing will permit of a slight further movement of the free end of the 60 curtain to the left which will be sufficient to fully close the opening in the frame 6. In the movement of the curtain to its open position the slot 11 in the bracket 8 will receive the extreme right-hand hanger 26,

thus permitting the curtain to be opened to its fullest extent. Likewise, when the curtain is closed, the slot 19 in the bracket 9 will receive the extreme left-hand hanger including the sections 30 and 31 so as to permit the curtain to be moved to a position 70 where it will fully close the door opening.

What is claimed is:

1. The combination with a frame, a trackway having an open top and a longitudinal slot in the bottom thereof; of a plurality of carriers movable in said trackway and insertable thereinto through said open top, a hanger connected to each carrier and projecting through said slot, a curtain supported by said hangers, and means connected to one of said carriers for moving said carriers in said trackway to adjust said curtain to open and closing positions. 75

2. The combination with a frame, a trackway having an open top and a longitudinal slot in the bottom thereof; of a plurality of carriers movable in said trackway and insertable thereinto through said open top, a hanger connected to each carrier and projecting through said slot, a curtain supported by said hangers, pulleys at each end of said trackway, and a flexible element extending around said pulleys and having an intermediate portion thereof connected to one of said carriers in said trackway to 90 adjust said curtain to open and closing positions. 95

3. The combination with a frame, a trackway having an open top and a longitudinal slot in the bottom thereof; of a plurality of carriers movable in said trackway and insertable thereinto through said open top, a hanger connected to each carrier and projecting through said slot, one of said hangers including pivotally connected sections, 100 a curtain supported by said hanger, and means connected to the carrier supporting the last named hanger for moving said hangers in said trackway to adjust the curtain to open and closing positions. 105

4. The combination with a frame; of brackets secured to the sides of said frame and provided with aligned slots, a trackway having its ends mounted in said brackets and provided with an open top and a longitudinal slot in the bottom registering with the slots in said brackets, a plurality of carriers movable in said trackway and insertable thereinto through said open top, a hanger connected to each carrier and projecting through the slot in said trackway, a curtain supported by said hangers, and means connected to one of said carriers for moving said carriers in said trackway to adjust said curtain to open and closing positions. 115 120 125
